CLAIM

The ornamental design for an infant seat, as shown and described.

DESCRIPTION

FIG. 1 is a perspective view of an infant seat, showing our new design;

FIG. 2 is a side perspective view of the infant seat of FIG. 1;

FIG. 3 is a rear perspective view of the infant seat of FIG. 1;

FIG. 4 is a left side view of the infant seat of FIG. 1;

FIG. 5 is a right side view of the infant seat of FIG. 1;

FIG. 6 is a left side view of the infant seat of FIG. 1, showing the rear leg retracting;

FIG. 7 is a top view of the infant seat of FIG. 1;

FIG. 8 is a bottom view of the infant seat of FIG. 1;

FIG. 9 is an elevated front view of the infant seat of FIG. 1; and,

FIG. 10 is an elevated rear view of the infant seat of FIG. 1.

The broken lines in the figures merely illustrate the environment for the infant seat of the present design and therefore form no part of the claimed design.
